Patented Nov. 6, 1973

229,038

NON-SPILL CONTAINER LID

Frank C. Schutz, 8547 Cherokee Drive,
Downey, Calif. 90241

Filed Oct. 10, 1972, Ser. No. 295,977

Term of patent 14 years

Int. Cl. D9—07

U.S. Cl. D9—257

FIG. 1 is a perspective view of a non-spill container lid showing my new design;

FIG. 2 is a top plan view;

FIG. 3 is a bottom plan view;

FIG. 4 is a cross-sectional view taken along line 4—4 of FIG. 2; and

FIG. 5 is a cross-sectional view taken along line 5—5 of FIG. 2.

I claim:

The ornamental design for a non-spill container lid, as shown.
